[57] CLAIM

The ornamental design for a cap, as shown and described.

DESCRIPTION

FIG. 1 is a front perspective view of a cap showing my new design; the broken line showing the outline of a head of a person and a circular patch or logo is for illustrative purposes only and forms no part of the claimed design;

FIG. 2 is a rear perspective view thereof;

FIG. 3 is a side elevational view, and the opposite side is a mirror image thereof;

FIG. 4 is a front elevational view thereof;

FIG. 5 is a rear elevational view thereof;

FIG. 6 is a top plan view thereof; and,

FIG. 7 is a bottom plan view thereof.

*Fig. 1.**Fig. 2.*

Fig. 3.

Fig. 4.

*Fig. 5.**Fig. 6.**Fig. 7.*
